TRAY FOR MEAT PATTIES

Harold L. Orlich, Greenville, and Philip A. Sanborn, Jr.,
Spartanburg, S.C., assignors to W. R. Grace & Co.,
Duncan, S.C.

Filed Jan. 4, 1972, Ser. No. 215,450

Term of patent 14 years

Int. Cl. D9—03

U.S. Cl. D9—189

FIG. 1

FIG. 2

FIG. 3

FIG. 4

FIG. 5

FIG. 6

FIG. 1 is a top perspective view of a tray for meat patties showing our new design;

FIG. 2 is a top view thereof;

FIG. 3 is a side elevational view thereof;

FIG. 4 is a sectional view thereof taken on line 4—4 of FIG. 4;

FIG. 5 is an end elevational view thereof looking from the left side of FIG. 2; and

FIG. 6 is a bottom plan view thereof.

We claim:

The ornamental design for a tray for meat patties, substantially as shown.
